UNITED STATES PATENT OFFICE

SAMUEL E. MORTIMER, OF LORAIN, OHIO, ASSIGNOR OF ONE-FOURTH TO WILLIAM V. CLAMPET, OF DAYTON, OHIO, ONE-FOURTH TO CARL E. HENNIES, OF CLEVELAND, OHIO, AND ONE-FOURTH TO JOSEPH F. GLIDDEN, OF LAKewood, OHIO

DRILL AND HOLE CLEANER

Application filed October 4, 1929. Serial No. 397,244.

My invention relates to an improved drill and hole cleaner, and has for its principal object a useful embodiment in manually operated drill for drilling rock, concrete and other mineral or hard material and which cleans the hole as it drills it. It is further improved over the prior patented art in that the entire device comprises telescoping parts having a common axis with the drill stem, including an outer barrel by which the tool may be held in one hand of the operator, and the drill stem and an upper reciprocating plunger are mounted in alignment within the outer barrel or cylinder. The axially-aligned parts are normally spaced apart by a compression spring which contacts directly an enlargement on the plunger and a detachable plug or closure at the bottom of the cylinder, while an inner end of the drill stem is positioned within the said spring coil but in no wise attached thereto.

It is a further object of my invention that the drill stem has a longitudinal, axial opening throughout its length, but for other reasons to be explained in this description, will need no valve for this opening, but will permit reciprocation of the plunger to force air into the opening.

It is a special advantage to support the said compression spring upon a directly attached portion of the cylinder and thereby serve to raise the said plunger to receive a fresh blow thereon delivered manually by the operator. Only the one spring is used or needed in my improved device.

In certain cases, I may use a sectional stem as a modified form shown in Figs. 10, 11, 13 and 14. Such construction has the advantage of permitting a change of the lower drill section without removal of the upper section. Further details will be explained later in the specification.

Other features of my invention will be explained by reference to the accompanying drawings showing the preferred embodiment thereof and in which—

Figure 1 is a longitudinal sectional view taken through my device, certain portions being broken away, and other parts shown in elevation;

Figure 2 is a transverse section shown in the plane indicated by the line 2—2 of Fig. 1;

Figure 3 is a transverse section shown in the plane indicated by the line 3—3 of Fig. 1;

Figure 4 is a transverse section taken in the plane indicated by the line 4—4 of Fig. 1;

Figure 5 is an end view of the drill stem;

Figure 6 is a perspective of a spring band device for detachable application to the stock;

Figure 7 is an elevation of the lower end of the stem and barrel attachment, with certain parts broken away to reveal the interior, and the angle of vision being at right angles to that shown in Fig. 1;

Figure 8 is a central, vertical section of a portion of the plunger and its enlargement, through one of the valves;

Figure 9 is a transverse section taken on the plane indicated by the line 9—9 of Fig. 8;

Figure 10 is a side elevation of my improvement embodying a modified form of drill stem, parts being broken away;

Figure 11 is a side elevation of the drill element shown in Fig. 10, but turned 90° on its vertical axis;

Figure 12 is an elevation of a separating device for use with the drill stem of Fig. 11;

Figure 13 is a transverse section of the stem shown in the plane indicated by the line 13—13 of Fig. 10, and

Figure 14 is a perspective view of the drill stem with the sections separated.

My drilling tool as a complete device, comprises an elongated cylinder 5 which readily serves as a tool stock whereby the tool may be held in proper position over the point to which the drill is to be applied, by one hand of the operator, while force is delivered to the plunger above. This cylinder is usually constructed of case-hardened nickel, steel or other suitable material. The upper end of this barrel is internally threaded to receive a flanged split collar 6 of suitable metal having reduced external threads 7 fitting the inner threads of the cylinder end.

The lower end of the cylinder 5 is also internally threaded at 8 to receive therein a

flanged split collar 9 which is centrally apertured at 10, and whose threaded portion 11 may engage the threads 8. One of the halves 12 of the collar 9 is radially apertured at 13 which latter is threaded at 14 to receive the threaded set screw 15 which engages the aligned apertures in the collar and cylinder wall, as disclosed in Figs. 1 and 4. The enlarged polygonal head 16 of the screw 15 10 serves to actuate the screw.

Externally of the lower end of the cylinder 5, a flexible band loop 17 is detachably mounted thereabout, parallel outwardly-bent tips 18 being cut out at a central point of said 15 loop 17, as at 19, whereby the tips 18 may be used to adjust the said screw 15 longitudinally in the apertures, and may also serve to hold the screw in position to lock the collar 9 in position in the cylinder wall, as well as 20 for other functions to be explained later. The loop 17 will be held against descending unduly, by its engagement of the flanges 20 of the collar 9. The collar 6 will be provided with a large aperture 21 for receiving an 25 axial plunger 22 to be later described.

The said plunger is provided with a cylindrical enlargement 23 which fits neatly within the cylinder 5 but prevents rising higher than the collar 6 and serves as a shoulder to limit 30 the rise of the plunger 22. Within the cylinder 5 and below the said enlargement, is mounted a coil spring 24 whose upper end presses against the enlargement 23 to hold the plunger normally to its upper limit, while the 35 lower end of the spring rests directly upon the collar 9. Fitted within the axial aperture of the collar 9 is a drill stem 25 having a central aperture 26 extending its entire length, the main part of the stem being of substantially 40 uniform radius, but the upper end of the stem having two longitudinally spaced heads or enlargements, the lower one 27 being outside of and fitting upwardly against the lower end of the collar 9, and the upper enlargement 45 28 positioned within the cylinder and having a radius somewhat less than that of the inner chamber of the cylinder 5.

The head 28 has an extreme upper position normally such as shown in Fig. 1, within 50 the cylinder 5 and above the collar 9, and the space between this head and the lower collar 9 may receive snugly therein a flexible tubular band 29 which will yield slightly to longitudinal movement of the stem and its head within 55 the cylinder. The lower end of the spring 24 surrounds this head 28.

The reduced portion 30 of the stem between the enlargements 27 and 28 is fitted within the aperture 10 of the collar 9 which being 60 split, is detachably mounted upon the portion 30, and may be secured to the lower end of the cylinder 5 by the threaded engagement 8. Very little movement of the member 30 in the collar is required, since the stem 25 65 is integral with the enlargements, and a blow

struck by the plunger 22 upon the part 28 is delivered directly to the drill point 31, the band 29 merely providing for a slight yielding movement of the stem relative to the cylinder, which cannot be great since the stem 70 will move downward for a distance hardly perceptible.

The set screw 15 has a reduced inner end 75 32 with which the stem portion 30 may have relative movement corresponding to that provided for by the band 29, by the provision of a slightly elongated external slot 33 in the part 30. The cylinder or barrel 5 has formed therein somewhat beneath the leather washer 34, one or more radial air inlet holes 35, and the cylindrical enlargement 23 has provided a plurality of longitudinal apertures 80 therethrough quite closely adjacent the periphery thereof. Each of these apertures through the head 23 includes a very small opening 36 85 leading downwardly into a larger chamber 37 carrying therein a ball 38, thereby providing a plurality of very delicate valves in the enlargement 23 which by momentum and by the reciprocation of the plunger 22 will operate by the upward movement of the ball to close the opening 36 and dropping downward in said chamber against a retaining pin 39 to open the valve.

The reciprocation of the plunger 22 will 90 operate the valves in the enlargement 23 by the momentum of the balls 38. The sudden descent of the plunger causes the balls 38 to rise relatively in the chambers 37 and close the openings 36, so that the air in the cylinder 5 is compressed to force air outward through the drill aperture 26 to blow out of it dust and dirt that may accumulate therein and thereby reducing friction.

A great disadvantage has arisen in 95 the past from the use of ball valves directly connected with the drill stem to prevent back suction of dirt through the axial opening in the drill stem. Such difficulty has been obviated more or less in 100 some constructions by providing a ball valve practically within such stem opening and intermediate its ends, but difficulty has arisen from such construction in the actuation of 105 the ball in such a valve, since the drill stem does not itself reciprocate, and a compression spring has been found essential to normally 110 close the valve. A further disadvantage in such a construction lies in the means necessary 115 for opening the stem for cleaning out and repairing the valve held within a central chamber of the drill. This I have overcome by providing the ball valve in the reciprocating plunger rather than in the drill stem, my 120 improved valve requiring no additional means other than momentum for actuating the ball which readily drops down upon the pin 39 when the plunger rises by the force of 125 the spring 24, and is effective in preventing 130 the spring 24, and is effective in preventing

the back suction of prior structures by opening the apertures 36.

While the valve apertures 36 are small, a plurality of the valves may be used, three being shown in Fig. 9, and more may be used if desired. This construction is especially advantageous in that it affords ready opening of the parts for cleaning the valves by merely removing the collar 6 and lifting out the plunger. This is a decided advantage, aside from the great reduction in the expense of manufacturing the stem part as an integral unit. The manufacture of the valve openings in the enlargement 23 is relatively inexpensive.

In Figs. 10 to 14 I have shown a sectional drill stem 40 whose upper section 41 is provided with a frusto-conical socket to receive a correspondingly shaped male portion 42 of the lower section of the stem which normally fits neatly within such socket, but permits the use of a plurality of lower sections.

The sections of the stem 40 will be provided with the axial opening 26 of the other form, and indeed, the structure of the entire upper portion of the section 41 will be like that shown in Fig. 1. A very narrow ledge or shoulder 43 on the lower section 44 will receive a portion of the impact of the plunger stroke, though the said socket 45 is fitted so closely upon the cone 42 that the sections will be held together without the provision of any other means. Additional means have however been provided for assisting the removal of the lower section 44 when a substitution of other sections therefor is desired. Such means, it has been found, may consist of a wedge member 46 designed to enter a space formed between the drill sections by cutting out a vertical face 47 on the cone 42 adjacent the shoulder 43 and cutting off an edge 48 of the section 41 to bear the force of the wedge 46 as the latter rests upon the shoulder 43. The insertion of the wedge or a slight tilting of the wedge serves to separate drill sections.

It is evident that my improved drill may be operated by the hand, compressed air, steam or electricity for drilling in very hard or semi-hard material.

Having set forth the principles of my invention, and described and illustrated an embodiment thereof for practical use, what I claim and desire to secure by Letters Patent, is,—

1. A combined hole drilling and cleaning device comprising an open ended cylinder, a plunger having longitudinal reciprocating movement in said cylinder and through its upper end and provided with an enlargement within the cylinder for limiting its upward movement, a drill point movable axially in the lower opening of the cylinder and having an unobstructed axial opening therethrough, an enlargement on the upper end

of said drill point movable axially within the cylinder for preventing disengagement of the cylinder and drill point, ball valves carried by said plunger enlargement to prevent back suction through said axial opening when the plunger moves upwardly but closing as the plunger descends, and a coil spring within the cylinder normally holding the plunger above and separate from the drill member.

2. A combined hole drilling and cleaning device comprising an open ended cylinder, a collar having an axial opening detachably secured in each end of the cylinder, a plunger having longitudinal movement in said cylinder and through its upper collar, a cylindrical enlargement on said plunger within the cylinder, a drill point extending through the lower collar of the cylinder and having an unobstructed axial opening therethrough, an enlargement on the upper end of said drill point positioned within the cylinder above the lower collar for preventing disengagement of the cylinder and drill point, ball valves carried by said plunger enlargement to prevent back suction through said axial opening of the drill point, the said valves closing and opening automatically as the plunger descends and rises, respectively, and a coil spring surrounding the plunger to normally hold the latter in its uppermost position.

3. A percussion drill comprising an open ended cylinder, a plunger longitudinally movable through the upper end of the cylinder and provided with means for limiting its upward movement, a drill stem in the lower opening of the cylinder having an unobstructed axial opening therethrough a threaded collar having an axial opening therethrough detachably secured to the lower end of the cylinder, the lower end of said cylinder having a radial pin adjustable toward and from an elongated slot in said stem to limit the lengthwise movement of said stem in the cylinder, and a coil spring resting upon a fixed portion of the cylinder and normally holding the plunger above the upper end of said stem.

4. A percussion drill comprising an open ended cylinder, a plunger longitudinally movable through the upper end of the cylinder, a cylindrical enlargement on said plunger within the cylinder for limiting the upward movement of the plunger, a drill point in the lower opening of the cylinder and having an unobstructed axial opening therethrough, an enlargement on the upper end of said drill point within said cylinder for preventing disengagement of the same from the cylinder, gravity ball valves carried by said plunger enlargement to prevent back suction through said axial opening in the drill point when the plunger moves upwardly but closing as the plunger descends,

and a coil spring surrounding the plunger and positioned between said enlargements to normally hold the plunger in its uppermost position.

5. A combined hole drilling and cleaning device, comprising an open ended cylinder having threaded collars with axial openings fitting the ends of the cylinder, a plunger mounted for reciprocation in the upper collar and provided with a cylindrical enlargement between its ends for reciprocation within the cylinder, a drill mounted in the opening of the lower collar and having an axial opening therethrough, a coil spring normally holding the plunger above the upper end of the drill, a gravity check valve mounted in the plunger enlargement radially outside the outline of the plunger to prevent back suction through said axial opening, the said valve closing and opening automatically as the plunger descends and rises, respectively.
